UNITED STATES PATENT OFFICE.

DEWITT C. CREGIER, OF CHICAGO, ILLINOIS.

WATER-SUPPLY FOR CITIES AND TOWNS.

SPECIFICATION forming part of Letters Patent No. 291,159, dated January 1, 1884.

Application filed March 9, 1882. (No model.)

To all whom it may concern:

Be it known that I, DEWITT C. CREGIER, residing in Chicago, Cook county, in the State of Illinois, have invented certain new and useful Improvements Relating to Water-Supply for Cities and Towns, of which the following is a specification.

I provide a supply of water under a high pressure, which shall be additional to and independent of the ordinary supply. The water, therefore, may be of a different quality from the ordinary water—as warm, muddy, or otherwise impure, or even salt. The water from my independent supply may be used to sprinkle streets, to supply fountains for ornamental purposes, and if the quality is proper for washing, supplying bathing establishments and manufactories for various purposes; but it is more especially designed for two great uses, in which a superior pressure is desirable—extinguishment of fires and the actuating of elevators and other machinery at points where it would be inconvenient and expensive to apply steam-power directly. I provide for maintaining a high and equable pressure on my independent system without requiring a reservoir or stand-pipe. The apparatus occupies but little space, and is largely automatic in its adaptation to the various conditions.

The accompanying drawings form a part of this specification and represent what I consider the best means of carrying out the invention.

Figure 1 is a vertical section through my device for securing uniformity of pressure in the high-pressure pipes. Fig. 2 is an elevation of the same. The elevation is mainly at right angles to the plane of section in Fig. 1, but the lower end of Fig. 2, represented as detached, is turned so as to stand in the same position as in Fig. 1 to better show the construction at that point. Fig. 3 is an elevation of the forcing and equalizing means on a small scale.

Similar letters of reference indicate like parts in all the figures.

The ordinary water-pipes (or system of water-distribution) are indicated by W. They are supplied with water at any available pressure, either from a river at sufficient elevation

or by pumping or otherwise. The pipes for my independent water system may be laid close to or at any required distance from the same.

A are the boilers; B, the stack; C, a steam-cylinder, and D a pump. These parts may be of any ordinary construction and arrangement; but it is essential that the furnaces and boilers shall have the capacity for generating a large amount of heat and supplying liberal quantities of steam in cases of emergency, as when several fires occur simultaneously, and also that the furnaces and boilers, by banking the fires or otherwise, shall be capable of maintaining the heat in the boilers with but little generation of steam, and without much consumption of fuel when but a small quantity of water is required, as during ordinary nights and Sundays. I make these operations partly automatic.

B' is a damper in the stack, and B² a rod connected to a lever controlling the same. By operating this rod the draft in the furnaces may be largely controlled.

C' is a throttle-valve or adjustable cut-off or expansion gear, and C² is a rod connected thereto. By operating this rod C² the consumption of steam in the engine, and consequently the rate of working of the engine and the rate of pumping may be varied between wide limits.

E is the pipe which conveys the water from the pump D to supply the city.

To the pipe E, near the pump, I provide an upright casing, F, having a stuffing-box, F', around the top and an annular ledge or internal flange, F², around the bottom. Within this plays a hollow cylindrical plunger, G, closed at the top and open at the bottom. This plunger, properly loaded, serves in two ways: first, it rises and sinks with fluctuations in the ratio of the supply to the demand for water; and, second, its hollow interior (tightly closed except at the bottom, where it is entirely open) serves as an air-chamber by imprisoning a quantity of air, and allowing the dividing-line between the air and the water to pulsate or rise and sink rapidly with momentary fluctuations in pressure due to the intermittent action of the pumps and analogous causes. Care is taken to supply air

through a small cock in the suction-pipe of the pump, or otherwise, so as to keep the interior of G always nearly filled, and thus to allow the plunger and its contents to serve with a large amount of elastic action. The loading of the plunger G is effected through separate weights G², which may be inserted and removed at pleasure, in the open-topped carriage G'. This carriage is bolted on the top of the plunger, and is guided by slides, of which I provide four, arranged as shown, connected to the casing F by arms F', and united at the top by a transverse framing, F''. It will be seen that when the water is consumed at precisely the same rate as it is supplied by the pumps the plunger G will remain stationary; but the air imprisoned therein will expand and contract as the pump alternately passes its points of maximum delivery and its minimum delivery or dead-point. The supply of water from the pumps to the casing F will be variable or intermittent; but the flow from the casing F to the city will be constant and the pressure nearly uniform. When the consumption in the entire city exceeds the supply by the pump, the pulsations in the water, due to the strokes of the pump, will continue to be extinguished, as before, by the elastic action of the air in the plunger G; but the general or mean pressure under the plunger being less than the gravity of the load on the latter, it will sink. When the consumption is less than the supply by the pump, the plunger will rise. H is a bell-crank lever turning on a fixed center, h, and carrying an adjustable weight, H', on its horizontal arm. The upright arm connects to the rod B², which operates the damper B' in the stack and controls the intensity of the fire. It also operates the rod C², which controls the consumption of steam in the engine and induces the engine, and consequently the pump, to change its speed the moment the lever H is changed in position. The horizontal arm of H rests on the rim of the carriage G'. Whenever the plunger G rises, indicating that the pump is working in excess of the power required, it lifts the weight H' and shifts the rods B² C², so that the engine consumes less steam and the draft in the furnaces is less, so as to produce less steam in the boilers. So soon as the consumption of water is in excess of the pumping the plunger G sinks, causing the lever H to sink, and consequently changing the position of the rods B² C² in the opposite direction, giving more steam to the engine and more force to the fire. A stop, F⁶, arrests the motion of the lever H when it has descended to the extent which will develop the maximum power of the apparatus, and the plunger may descend its full extent, performing its other functions of equalizing the flow without influencing the steam by any motion while it is in a low position; but so soon as the pumping has been sufficiently quickened to raise the pressure throughout the city from its minute diminution again to the proper standard, the carriage G' again rises into contact

with the lever H and reduces the consumption of steam and the motion of the engine and pump. I believe that the control of the engine by this automatic arrangement will be complete; but the control of the fires in changing from extreme conditions will require one or more attendants.

The high pressure exerted by the water in my system will work elevators and other small powers at any reasonable height in the city. It will force the water up through permanent systems of fire-pipes, with which many modern manufactories and other large buildings are provided. It will supply water with more than ordinary facility, and afford great assistance to the action of steam fire-engines and hand-engines. It will also in many or all portions of the city supply water directly from hydrants under sufficient pressure to be available by simply attaching a hose without imparting to the water any further power than is due to the pressure of the mains. I propose to make this last mode of operation especially available by providing special hydrants in those vicinities where the expense is warranted, and provide a supply of hose in the immediate vicinity of the hydrants. The owner, a private watchman, or any properly-authorized party running to the hydrant with facilities for opening, can let on the water and make immediately available a sufficient length of hose to extend to the point desired and throw a stream immediately with the full force due to the high pressure in the street-mains. I attach much importance to the fact that by varying the weights G² in carriage G', attached to the plunger G, I can vary the pressure in the high-pressure pipes W, while the automatic devices will maintain the pressure uniform after the proper degree of pressure in that system of pipes has been attained. Thus under ordinary conditions the pump D may work against the ordinary moderate resistance, the number of weights G² in the carriage G' being small; but when a fire occurs and the opening of a number of hydrants calls for much water, I can, by increasing the number of weights G² and correspondingly quickening the fires, soon change the action by delivering the water into the high-pressure system at a greatly increased pressure, thus maintaining the full action of elevators and other machinery depending on this force, and even materially aiding the fire-engines.

The hydrant and hose may be made the subject of a separate application for patent.

I do not here claim the special device for equalizing the pressure of the water, such being made the subject of a separate patent dated May 9, 1882, No. 257,557. I can vary the forms and proportions of the parts which effect the automatic regulation, and which call the attention of the attendant to an excessive elevation or depression of the plunger.

The junction of the pipe E to the plunger-case F may be enlarged and rounded.

There is no objection to the use of pure fresh

water for my independent system, where it can be obtained.

Among uses for my independent system not before suggested or sufficiently explained, are 5 the extinguishment of fires by ready connections to stand-pipes mounted permanently on the exterior or the interior of buildings, the sprinkling and washing of sheets, the thawing of snow when the water is from a relatively 10 warm stream, and especially when it is salt-water from the sea, the effect of salt in rapidly melting snow and ice being long known and often used in other branches of the arts.

The water from my high-pressure independent system may also be made very useful in 15 working passenger-elevators, freight-elevators, ventilating devices, devices for simply agitating the air by fans, blowing organs, and working small and large machines generally; 20 also for special and general sanitary objects and purposes. Its strong force and copious supply, when required, may also at rare inter-

vals be of great service in aid of police and military in disconcerting and breaking up riotous assemblages in the streets.

25

I claim as my invention—

In a water-supply for cities and towns, wherein the water is supplied under separate high and low pressures, and in combination with the duplex series of pipes W and E and 30 the pump D, the plunger G, carriage G', and adjustable weights G², for varying the pressure in high-pressure pipes, and the devices, substantially as described, for maintaining the pressure uniform after the proper degree has 35 been attained, as set forth.

In testimony whereof I have hereunto set my hand, at Chicago, Illinois, this 1st day of March, 1882, in the presence of two subscribing witnesses.

DEWITT C. CREGIER.
